IRONING BOARD

Hiram E. Smith, Glenview, Ill.

Application November 25, 1955, Serial No. 548,997

3 Claims. (Cl. 38—135)

This invention relates to ironing boards, and more particularly has reference to an ironing board having a main or body portion, to which a plurality of extensions are hinged, with said extensions being selectively swingable to produce various combinations or types of ironing boards in a single unit.

Heretofore, the general practice has been to provide an ironing board in which the surface on which the garments being ironed are supported is of unchanging length and width. As a result, when it is desired to use a sleeve board, it has been necessary that a separate unit, having a small body portion over which a shirt sleeve or the like can be positioned, be used. This is usually kept separately from the conventional ironing board, and is sometimes placed upon the ironing board when sleeves are to be ironed.

This represents a somewhat inconvenient arrangement. The sleeve board must be so disposed as to be readily accessible, and during a single period of ironing, it may be necessary that the sleeve board be placed on and removed from the ironing board proper a number of times.

In view of the above, it is proposed to provide an ironing board which has a hinged extension that can be swung upwardly to a position in which it is folded over the body portion of the ironing board, to expose below the ironing board a sleeve board, conveniently disposed for use. The sleeve board and the ironing board proper, thus, are in accordance with the present invention a self-contained unit foldable in the same manner as a conventional ironing board, and occupying when not in use no more space than that required by a conventional board.

Another object of importance is to provide a device of the nature referred to wherein a plurality of sleeve boards can be incorporated in a single ironing board structure, with said sleeve boards being of different sizes, so as to be capable of being selectively employed, according to the needs of the particular situation.

Still another object is to provide a combination ironing board as described which can be mounted on any of various conventional foldable stands without requiring modification or redesign of said stands.

Still another object is to provide a hinge or folding ironing board assembly so designed that whichever surface is being ironed upon will still be maintained wholly rigid.

Still another object is to provide an ironing board of the type stated that will be capable of manufacture with little or no increase in cost above that presently required to manufacture a conventional ironing board and a set of sleeve boards to be used in association therewith.

Other objects will appear from the following description, the claims appended thereto, and from the annexed drawing, in which like reference characters designate like parts throughout the several views, and wherein:

Figure 1 is a perspective view of an ironing board formed according to the present invention, as it appears when erected, ready for use;

2

Figure 2 is a longitudinal sectional view on line 2—2 of Figure 1;

Figure 3 is a transverse sectional view on line 3—3 of Figure 2;

5 Figure 4 is a fragmentary perspective view showing the extension of the ironing board folded back for exposing the upper one of a pair of sleeve boards of different sizes;

10 Figure 5 is a view similar to Figure 4 in which the upper sleeve board has been folded back to expose the smaller sleeve board; and

Figure 6 is a greatly enlarged, detail sectional view of the hinge connection between the several boards, on line 6—6 of Figure 1.

15 A conventional stand 10 (any of various conventional stands may be used with the invention) is shown supporting an ironing board including a lower sleeve board 12, a main ironing board portion 14, an upper sleeve board 16, and an extension 18 of the portion 14.

20 Lower sleeve board 12 extends substantially the full length of the ironing board structure, and is formed from a single length of wood, metal, or the like, having a body part 20. Connected pivotally at their upper ends to the main part 20 are the rear legs 22 and front legs 24 of stand 10, suitably braced as at 26, 28.

25 The elongated flat, wide body part 20 tapers at one end to merge into an elongated, slightly tapering, lower sleeve board member 30 suitably covered and padded, and lying in a plane common to that of body part 20.

30 The main ironing board portion 14 comprises a wide, generally rectangular member 32 wider than body part 20 and supported thereon in face-to-face contact therewith. This is also suitably padded and covered, and is fixedly secured to the body part 20. Substantially at the inner end of member 30, the member 32 terminates and is formed with a transverse, right-angular recess 34 defining a forwardly projecting transverse tongue 36 thereon. In the opposite ends of the recess, hinge plates 38 are secured by screws 40.

35 40 The upper sleeve board 16 comprises a gradually tapering, suitably padded and covered member 42 wider at its base than member 30 and terminating at its free end slightly inwardly from the free end of member 30. Thus, when a wide, thick sleeve board is needed the members 30, 42 cooperate to provide the same, as shown in Figure 4. When a thinner, narrower sleeve board is desired, member 30 is used alone (see Figure 5).

45 Member 42 at its inner end is integrally formed with a reduced, right-angled hinge plate extension 44, extending between the hinge sleeves of plates 38 and having hinge sleeves aligning with those of plates 38 to receive a hinge pin 46. Upper sleeve board 16 is thus swingable about an axis extending transversely of main portion 14 and disposed substantially in the plane of the top surface of portion 14. In its use position, member 42 lies in a plane offset downwardly from and paralleling that of said top surface, with the reduced extension 44 defining side shoulders 48 engaged by tongue 36 (see Figures 4 and 6) to limit the downward swinging movement of the member 42.

50 55 The extension 18 of the main portion 14 includes an extension member 50 in the upper surface of which are recessed hinge plates 52 (Figures 1 and 6) having hinge sleeves through which extend hinge pins 54. These pass through double hinge sleeves 56 alternating with the hinge sleeves of the plates 38, 52 and receiving also the hinge pin 46. The hinge pin 46 extends in closely spaced, parallel relation to the coaxial hinge pins 54.

60 65 In its use position, the extension member is coplanar with the main member 32, and is supported at its inner end on tongue 36 (see Figure 6) above and parallel to the members 42, 30.

To interlock the members 50, 42 against relative swinging movement when member 50 is in its use position, extension 44 of member 42 has a recess or indentation 58 (Figure 4) into which extends a projection 60 on the inner end of member 50. The projection may further be appropriately said to serve as an abutment relieving strain on the hinge connections when pressure is exerted on the member 50 during the ironing of articles thereon, and further may be rubber covered or otherwise resiliently faced to provide a cushioned stop when member 50 is swung from its Figure 4 to its Figure 1 positions.

To the underside of the free end portion of member 50 there is secured a block 62 which provides a spacer (see Figure 2) between the lower sleeve board 12 and the main board portion extension 18, further relieving strain on the hinge connection so that the extension 18 when in use is supported at both ends. The block is recessed at 63 to receive the free end of the upper sleeve board 16, and pivoted on the block is a locking handle or keeper 64 which is swingable under the lower sleeve board 12 (Figure 2) for locking the upper sleeve board 16 and the extension 18 against swinging movement out of their extended positions.

In use, the ironing board is used in a conventional manner with the several components thereof disposed as in Figure 1. If a wide sleeve board is desired, the extension 18 is merely swung over onto the main portion 14 as in Figure 4. If a narrower, thinner sleeve board is desired, the upper sleeve board 16 is now swung over onto the extension 18 as in Figure 5. Thus, in a single ironing board structure, there are provided a main ironing board member, and two different sleeve boards, any of which can be disposed for use merely by a swift, easy swinging adjustment of selected components of the structure. At the same time, the overall size of the structure, both in its extended and collapsed conditions, is little or no greater than that of a conventional ironing board, and there is far less storage space required than that needed for storing a conventional ironing board plus a conventional single or double sleeve board. These desirable characteristics are obtained it is believed, by the use of the novelly formed hinge arrangement, permitting the swinging parts to lie flat on top of one another when in their Figures 4 or 5 positions, while yet insuring the coplanar relationship of the main board portion 14 and its extension 18 when the ironing board is being used in the regular manner.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. An ironing board comprising a main ironing board portion; a sleeve board underlying said board portion and having a fixed connection to and projecting beyond one end of said portion; a main board portion extension hinged to the main portion to swing between a first position in which it overlies the main portion to expose the sleeve board for use, and a second position in which it overlies the sleeve board in coplanar relation with the main portion; and lock means releasably interengaging the sleeve board and said extension with each other in the second position of the extension, comprising a block

secured to the underside of the extension and a keeper pivoted on the block and engageable under the sleeve board, said block extending as a spacer between the sleeve board and extension at one end of the extension to support the extension on the sleeve board at said end thereof, the main portion including a tongue at the hinged end of said extension extending as a spacer between the sleeve board and extension at the other end of the extension to provide a support for said other end of the extension.

2. An ironing board comprising a main ironing board portion; a sleeve board underlying said board portion and having a fixed connection to and projecting beyond one end of said portion; a main board portion extension hinged to the main portion to swing between a first position in which it overlies the main portion to expose the sleeve board for use, and a second position in which it overlies the sleeve board in coplanar relation with the main portion; lock means releasably interengaging the sleeve board and said extension with each other in the second position of the extension, comprising a block secured to the underside of the extension and a keeper pivoted on the block and engageable under the sleeve board, said block extending as a spacer between the sleeve board and extension at one end of the extension to support the extension on the sleeve board at said end thereof, the main portion including a tongue at the hinged end of said extension extending as a spacer between the sleeve board and extension at the other end of the extension to provide a support for said other end of the extension; and a second sleeve board hinged at one end to the main portion to swing independently of the extension and extending between the first sleeve board and said extension, said second sleeve board having a shoulder adjacent said end thereof engaging said tongue in the second position of the extension.

3. An ironing board comprising a main ironing board portion; a sleeve board underlying said board portion and having a fixed connection to and projecting beyond one end of said portion; a main board portion extension hinged to the main portion to swing between a first position in which it overlies the main portion to expose the sleeve board for use, and a second position in which it overlies the sleeve board in coplanar relation with the main portion; lock means releasable interengaging the sleeve board and said extension with each other in the second position of the extension, comprising a block secured to the underside of the extension and a keeper pivoted on the block and engageable under the sleeve board, said block extending as a spacer between the sleeve board and extension at one end of the extension to support the extension of the sleeve board at said end thereof, the main portion including a tongue at the hinged end of said extension extending as a spacer between the sleeve board and extension at the other end of the extension to provide a support for said other end of the extension; and a second sleeve board hinged at one end to the main portion to swing independently of the extension and extending between the first sleeve board and said extension, said second sleeve board having a shoulder adjacent said end thereof engaging said tongue in the second position of the extension, the block being recessed to receive the other end of the second sleeve board.
